UNITED STATES PATENT OFFICE.

HENRY P. CLAUSEN, OF MOUNT VERNON, AND CHARLES L. GOODRUM, OF NEW YORK, N. Y., ASSIGNORS TO WESTERN ELECTRIC COMPANY, OF NEW YORK, N. Y., A CORPORATION OF NEW YORK.

TELEPHONE-EXCHANGE SYSTEM.

1,386,688.

Specification of Letters Patent.

Patented Aug. 9, 1921.

Application filed June 5, 1919. Serial No. 302,031.

To all whom it may concern:

Be it known that we, HENRY P. CLAUSEN and CHARLES L. GOODRUM, citizens of the United States, residing at Mount Vernon, 5 in the county of Westchester and State of New York, and at New York, in the county of New York and State of New York, respectively, have invented certain new and useful Improvements in Telephone - Exchange Systems, of which the following is a full, clear, concise, and exact description.

This invention relates to machine switching telephone systems, and particularly to such systems in which special service features are included.

The object of this invention is to provide an arrangement whereby special service designed to expedite the work in a commercial office may be given.

20 A feature of the invention is the manner in which several telephone lines are multiplied in the terminals of a connector switch, the same lines arranged in several groups, the several lines appearing in a different order in each group.

Let us assume the case of the office of the patent department of a great telephone manufacturing company. The attorney S has charge of a group of attorneys all 30 working on the prosecution of applications relating to automatic telephony. K, one of the attorneys reporting to S, is working on applications dealing with power drive systems, while another attorney H is working 35 on applications dealing with step-by-step systems.

A party desiring general information about automatic telephone systems may call S, but finds his line busy. K, however, could 40 probably give the desired information, and it would expedite matters if he could be automatically reached under the circumstances. Furthermore, both S and K might be busy, in which case H might be able to 45 give the desired information or at least tell the calling party that he could procure such information and would call him back. In this case it would expedite matters if H could be automatically reached. In another 50 case, the party calling for specific information on power drive systems in calling K might find K's line busy, but H might be able to help out, or in case he too is busy,

S might be able to give the desired information. In a third case, a party calling for 55 specific information on step-by-step systems in calling H might find his line busy. It would be expedient in that case to have the call automatically directed to S or to K in turn.

A feature of the invention is therefore the provision of means for calling any desired line of a group of lines, and in case that such line is busy, to automatically direct the call to other lines of the group leading in 60 turn to parties next in ability to give the desired information or subordinate to the first for the particular service desired. This and other features of the invention will 65 more fully appear in the following description and the appended claims.

Special notice is directed to the arrangement of the called lines. The group of called lines for the use of S, K and H are connected to several groups of terminals in 70 the connector switch in different orders. In the first group they appear in the order S, K and H; in the second group K, H and S, and in the third group H, S and K. Thus, any one of the three lines may be 75 reached by a directive setting of the connector switch. If the line thus selected is busy, the connector is arranged to automatically select one of the others.

It is not necessary that the groups of 80 called lines be arranged as shown in the drawing, that is, all on one level, but might be widely separated, their positions depending on the numbers of the first line in each group.

In the figure of the drawing, a calling 85 substation is indicated at the left-hand side, the circuit of a trunk-hunting connector is diagrammatically shown at the center, and the multiplied arrangement of three called lines with their connections to the terminals of a connector switch is shown at the right-hand upper corner.

Let us assume that the calling party, as 90 in the case assumed, wishes specific information on a certain question dealing with power drive automatic telephone systems, and therefore makes a call to K's line. The calling party removes his receiver at the substation 1, whereupon he is connected in 95 105 any well-known manner to the connector

switch 2. Upon the seizure of this connector switch, the line relay 3 is energized and attracts its armature. A circuit is thereupon established from ground, the armature and 5 front contact of relay 3, the armature and contact of relay 4, the winding of relay 5, to battery and ground. Relay 5 is energized and attracts its armatures. The calling party now manipulates his dial 6 to directly set the brushes 7, 8 and 9 on the 10 terminals of K's line. The first series of impulses transmitted by the dial 6 consists of a series of interruptions in the line circuit, whereby the armature of relay 3 is vibrated. Upon each retraction thereof, a 15 circuit is completed from ground, the armature and back contact of relay 3, right-hand armature and front contact of relay 5, the side switch arm 10 and its first position contact, the primary magnet 11, to battery and ground, whereby the primary magnet acts 20 to step the brushes 7, 8 and 9 to the level in which K's line appears. This series of impulses transmitted to the primary magnet 25 11 also energizes the left-hand winding of escape magnet 12, whereby it attracts its armature and retains it in this position until the end of this series of impulses. When these impulses have been all transmitted, 30 the relay 3 retains its armature in the actuated position and allows the escape magnet to de-energize, the side switch wipers are passed into their second position.

The subscriber at substation 1 now manipulates his dial 6 to set the brushes 7, 8 and 35 9 on the terminals of K's line. These terminals are shown as 13, 14 and 15. In the same manner that the primary magnet was actuated, the secondary magnet 16 is now 40 actuated, and the brushes 7, 8 and 9 are set on the terminals 13, 14 and 15.

We will assume that K's line is busy. That means that a ground will be found on the terminal 15, whereupon a circuit will 45 be completed from ground, terminal 15, brush 9, side switch wiper 17 and its second position contact, and as soon as the armature 18 has been released, through the contact and armature 18, the left-hand winding of 50 escape magnet 12, to battery and ground. The escape magnet 18 is arranged in the same manner as the side-switch magnet shown in the patent to Goodrum, No. 1,202,281, granted Oct. 24, 1916, in such a 55 manner that the armature 18 will make its contact before the escape magnet allows the side-switch wipers to pass into their next position. Hence, as soon as the armature 18 completes the circuit just described, the 60 escape magnet will again be energized. Since the side-switch wipers are in their second position, the closure of this circuit will also close a circuit through the side-switch wiper 10 and the secondary magnet 65 16, whereby the brushes 7, 8 and 9 will be

stepped on to the next set of contacts. If the line connected to this set of contacts is also busy, the brushes will in the same manner be stepped on to the set of contacts 70 19, 20 and 21, which lead, as in the case assumed, to S's line. S's line being idle, no ground will be found on the contact 21, and hence upon the release of the armature 18, the escape magnet 12 will not again be energized and will cause the passage of the side-switch wipers into their third position. 75

In this position, ringing current is supplied through the windings of the relay 4, the side-switch wipers 22 and 23, the brushes 7 and 8, the terminals 19 and 20 to the call bell 80 of the substation 24. Upon the response of the called subscriber, relay 4 will be energized sufficiently to actuate its armature, which opens a short circuit over the right-hand winding of magnet 12 and includes it 85 in the circuit of relay 5. Magnet 12 will be energized in this circuit, and upon its energization will pass the side-switch wipers into their fourth position, whereupon conversation may take place. 90

When the calling and called subscribers replace their receivers on their hooks, relays 3 and 25 will become de-energized, and relay 5 will, in response to the de-energization of relay 3, also become de-energized. Thereupon, a circuit will be established from ground, the armature and back contact of relay 3, the right-hand armature and back contact of relay 5, the left-hand armature and back contact of relay 25, left-hand 100 armature and contact of relay 5, right-hand armature and contact of relay 25, the primary off-normal contact 26, winding of release magnet 27, to battery and ground, which will cause the release of the connection in the well-known manner. 105

Should all of the lines of the group have been busy, the brushes 7, 8 and 9 would have passed to the set of busy contacts 28, 29 and 30, and the side-switch wipers 22 and 23 pass into their third position as described. In this position a circuit would have been established from ground, the secondary winding of BZ, contact 28, brush 7, side-switch wiper 22 in its third position, left-hand winding of relay 4, through a source of ringing current, and the current traveling over this path would have been sufficient to energize the relay 4, whereby the side-switch wipers would have been passed into their 110 fourth position as has been described. In this position the tone from the source BZ would have been transmitted to the calling substation and the subscriber there notified that all lines, over which he might get the 115 desired information were busy, and he would thereupon hang up and release the connection. 120

What is claimed is:

1. In a telephone system, line terminals, 130

a group of lines terminating in several groups of terminals in various orders of subordination, a calling line, and means for extending said calling line to any one of 5 said lines in said group and responsive to the busy condition of said line to automatically extend said calling line to the next in turn subordinate line.

2. In a selecting system, circuit terminals, 10 a group of circuits terminating in several groups of terminals in various orders of subordination, means for selecting any one of said circuits, and means for automatically

selecting a subordinate circuit if the first one selected is busy. 15

3. In a selecting system, circuit terminals, a group of circuits terminating in several groups of terminals in various orders of subordination, and means for selecting any one of said circuits and for thereafter automatically selecting a subordinate circuit. 20

In witness whereof, we hereunto subscribe our names this 28th day of May, A. D. 1919.

HENRY P. CLAUSEN.
CHARLES L. GOODRUM.
